UNITED STATES PATENT OFFICE

140,812

DESIGN FOR A HOLSTER

Sol Dobrin, New York, N. Y.

Application January 4, 1945, Serial No. 117,250

Term of patent 7 years

(Cl. D22—6)

To all whom it may concern:

Be it known that I, Sol Dobrin, a citizen of the United States of America, residing in New York city, county of Kings, and State of New York, have invented a new, original, and ornamental Design for a Holster, of which the following is a specification, reference being had to the accompanying drawing, forming part thereof, wherein

The rear of the holster is substantially plain in appearance.

I claim:

The ornamental design for a holster, substantially as shown and described.

SOL DOBRIN.
